EVENER.

1,089,927.

Specification of Letters Patent. Patented Mar. 10, 1914.

Application filed April 22, 1913. Serial No. 762,774.

To all whom it may concern:

Be it known that we, ROBERT H. KEITH and FRED H. Brooks, citizens of the United States, and residents of Rowan, in the county of Wright and State of Iowa, have made certain new and useful Improvements in Eveners, of which the following is a specification.

Our invention is an improvement in eveners, and has for its object to provide a device of the character specified especially adapted for use with farming implements of the drag class, especially of the folding type, and so arranged that the evener may be folded with the drag, in passing through gates or narrow passages.

In the drawings: Figure 1 is a front view of the improved evener, Fig. 2 is a top plan view, Fig. 3 is a partial front view showing one of the sections folded, and Fig. 4 is an enlarged section on the line 4—4 of Fig. 2.

The present embodiment of the invention comprises a central section 1, and lateral sections 2, the said section being of wood or like suitable material of suitable cross section. The central section is provided at each end with oppositely arranged hinge leaves, each of the said leaves comprising a plate 3 adapted to be arranged longitudinally of the side edge of the section, and provided at its outer end with a lateral perforated lug 4. The opposite hinge leaves at each end of the section are secured to the section by bolts 5, and a ring 6 is connected to the front hinge leaf at each end, by means of a staple 7. Each of the lateral sections 2 is provided at its inner end with a pair of oppositely arranged hinge leaves, each leaf consisting of a plate 8 adapted to be arranged alongside the edge of the section, and having a lateral lug 9 at its inner end, the said lug being perforated, and registering with the lug 4 of the adjacent leaf section on the central section. The hinge leaves at the inner end of each of the lateral sections are secured together and to the section by means of bolts 10, and a ring 11 is connected with the hinge leaf at the front edge of each lateral section, by means of a staple 12. The hinge leaves of the lateral section are seated in recesses or countersinks 13 in the side edges of the said lateral sections, and the hinge leaves of the central section are seated directly on the side edges 55 of the said section. This arrangement permits the lugs 9 of the hinge leaves of the

lateral sections to fit inside the lugs 4 of the hinge leaves of the central section, and a pin or bolt 14 is passed through the registering openings of the lugs 4 and 9, to hinge 60 the lateral sections to the central section. The central section is provided on its upper face at each end and at each side edge with a recess 15, and each of the lateral sections is provided at its inner end on its upper face 65 and at each side edge with a similar recess 16, each recess of the lateral sections registering with a recess at the adjacent end of the central section.

A pair of cross levers 17 and 17^a respectively, is pivoted to each lateral section, on the upper face thereof, by means of a bracket 18, the said bracket having each of its ends offset downwardly onto the upper face of the adjacent section, and secured 75 thereto by means of bolts or screws 19. The levers 17 and 17^a are crossed intermediate their ends, and a common bolt 20 connects the said levers to the bracket, a nut 21 engaging the bolt below the bracket to hold 80 the parts in place. Each lever 17 and 17^a is provided at its outer end with a grip 22, and the said grips are spaced apart and arranged parallel, to permit both to be grasped to swing the said levers on their pivotal 85 connection. On the opposite side of the pivot from the grips, each lever is given a quarter turn, and the inner extremity of each of the said levers is provided with an opening for receiving the adjacent bolt or 90 pivot pin 14. The levers 17 and 17^a engage the bolt just inside the adjacent lug 9, and a latch plate 23 is connected with the bolt at each end, just inside the adjacent lever 17 or 17^a as the case may be. Each latch plate 95 has its lower end offset outwardly, as indicated at 24, and received in the adjacent registering recesses 15 and 16 of the central and lateral sections, and the said offset end of each plate is provided with a lateral out- 100 wardly extending pin 25. Each hinge leaf 3 and 8 at the adjacent side of the central and lateral sections is provided with an opening in the recesses, for engagement by the adjacent pin 25, when the lateral sections are in alinement with the central section. The said openings, 26 for the leaf 8 and 27 for the leaf 3, are adapted to register when the sections of the evener are in alinement, for engagement by the pin 25 of 110 the adjacent latch plate to lock the sections in alinement. A coil spring 28 encircles the

bolt 14 between the latch plates, and normally presses the said latch plates away from each other. The recesses 15 and 16 are of sufficient depth to permit the latch plates to move inwardly far enough to disengage the pins 25 from the adjacent openings 26 and 27. When the outer ends of the levers 17 and 17^a are moved toward each other, the inner ends of the said levers are also moved toward each other, thus moving the latch plates 23 inwardly, against the resistance of the spring 28, to disengage the pins 25 from the registering openings, whereby to release the evener sections and to permit them to be folded upon each other. The lugs 4 and 9 are of sufficient length to permit either lateral section to fold over upon the central section in parallel relation. Each of the lateral sections is provided near its outer end and on its front edge with a ring 29, secured to the section by a staple 30.

In operation, when it is desired to fold the evener, the outer ends of the levers 17 and 17^a are pressed together, thus moving the inner ends inwardly toward each other, compressing the spring 28, and moving the latch plates to disengage the pins 25 from the registering openings of the hinge leaves. Either lateral section may be then folded over upon the central section, as indicated by the arrows in Fig. 1. One of the said lateral sections will be adjacent to the central section, and the other lateral section may be folded over upon the first-named lateral section. In moving through a narrow passage, either lateral section may be folded, or if the passage is too narrow to permit the passage of the central section and one lateral section in alinement, the other lateral section may be folded over upon the first-named section. The coil spring 28 holds the latch plates with the pins 25 in engagement with the openings of the hinge leaves, thus absolutely preventing any accidental folding of the evener.

It will be evident that the evener may be composed of any number of sections, three being shown, since this is the usual form of the evener.

50 Sectional drags and harrows are usually constructed of three sections, and when moving through narrow passages the side sections are turned up into approximately vertical position. With the improved evener, the lateral sections of the evener may be connected to the lateral sections of the harrow or drag, and when the drag or harrow is folded the lateral section may be folded therewith.

60 The sections of the evener are not intended to fold into parallelism. One of the lateral sections will fold into parallelism on the central section, and the other lateral section may be partially folded. If it is desired to 65 fold the three sections in parallelism, the

set of lugs 4-6 at one end of the central section must be of greater length than the set at the other end. With long eveners, the central section will be long enough to permit the lateral sections to fold end to end. 70

We claim:—

1. A device of the character specified, comprising a central and lateral sections, a pair of hinge leaves arranged at each end of the central section on opposite sides thereof, each leaf having a lateral upwardly extending perforated lug, a pair of hinge leaves secured to the inner end of each lateral section on opposite sides thereof, each leaf having a lateral upstanding perforated lug fitting inside and registering with the lug of the adjacent hinge leaf of the central section, a pivot pin passing through the perforations, the meeting ends of the section being recessed at each side edge at the lugs, and the adjacent hinge leaves at each side of the sections having registering openings when the sections are in alinement, a latch plate on each pivot pin at each side of the sections, each latch plate depending into the adjacent recess and having a lateral pin for engaging the openings of the leaves to lock the sections in alinement, a spring encircling each pivot pin and normally pressing the latch plates outwardly, and means for simultaneously moving the said plates inwardly to release the pins, said means comprising crossed levers adjacent to each pin, said levers being pivoted at their intersection to the adjacent lateral section and having their inner ends provided with openings for engaging the pivot pins between the latch plates and the adjacent lugs of the hinge leaves. 90

2. A device of the character specified, comprising central and lateral sections, a pair of hinge leaves arranged at each end of the central section on opposite sides thereof, each leaf having a lateral upwardly extending perforated lug, a pair of hinge leaves secured to the inner end of each lateral section on opposite sides thereof, each leaf having a lateral upstanding perforated lug fitting inside and registering with the lug of the adjacent hinge leaf of the central section, a pivot pin passing through the perforations, the meeting ends of the sections being recessed at each side edge at the lugs, and the adjacent hinge leaves at each side of the sections having registering openings when the sections are in alinement, a latch plate on each pivot pin at each side of the sections, each latch plate depending into the adjacent recess and having a lateral pin for engaging the openings of the leaves to lock the sections in alinement, a spring encircling each pivot pin and normally pressing the latch plates outwardly, and means for simultaneously moving the said plates inwardly to release the pins. 110

3. A device of the character specified, comprising a central and lateral sections, a pair of hinge leaves arranged at each end of the central section on opposite sides thereof, each leaf having a lateral upwardly extending perforated lug, a pair of hinge leaves secured to the inner end of each lateral section on opposite sides thereof, each leaf having a lateral upstanding perforated lug fitting inside and registering with the lug of the adjacent hinge leaf of the central section, a pivot pin passing through the perforations, the meeting ends of the sections being recessed at each side edge at the lugs, and the adjacent hinge leaves at each side of the sections having registering openings when the sections are in alinement, a latch plate in each recess and having a pin for engaging the openings of the leaves to lock the sections in alinement, means for holding 20 each pair of latches in engaging position, and means for simultaneously releasing each pair of latches.
4. A device of the character specified, comprising a central and lateral section, a hinge connection between the inner end of each lateral section and the adjacent end of the central section, means for locking the sections in alinement, and means on each lateral section for releasing the device lock- 25 30 ing means.
